(57) **CLAIM**

The ornamental design for an MRI coil, as shown and described.

DESCRIPTION

FIG. 1 is a top front perspective view of an MRI coil, illustrated in accordance with the present disclosure;

FIG. 2 is a bottom front perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines depict portions of the MRI coil that form no part of the claimed design; the broken lines form no part of the claimed design.

1 Claim, 7 Drawing Sheets

FIG. 1

FIG. 2

FIG. 3

FIG. 4

FIG. 5

FIG. 6

FIG. 7

FIG. 8
